UNITED STATES PATENT OFFICE.

CARL SMYRSKI AND JAN LORENC, OF PHILADELPHIA, PENNSYLVANIA.

TORPEDO-PROTECTING DEVICE FOR SHIPS.

1,248,940.

Specification of Letters Patent.

Patented Dec. 4, 1917.

Application filed June 28, 1917. Serial No. 177,500.

To all whom it may concern:

Be it known that we, CARL SMYRSKI and JAN LORENC, a subject of the Emperor of Austria and a citizen of Russia, respectively, 5 residing at Philadelphia, in the county of Philadelphia and State of Pennsylvania, have invented certain new and useful Improvements in Torpedo-Protecting Devices for Ships, of which the following is a specification.

This invention relates to certain new and useful improvements in torpedo protecting devices for ships.

The primary object of the invention is the provision of a protector adjustably carried substantially surrounding the hull of a vessel whereby torpedoes and other projectiles will be prevented from striking the ship and causing injury thereto.

20 A further object of the device is to provide a protector against torpedoes which are adapted to travel near the water line, the present device affording protection at this point in the form of a resisting armor which 25 missiles will be incapable of penetrating.

A still further object of the invention is the provision of a vertically adjustable armor for ships' hulls adapted for removably positioning thereon, and which is readily 30 shifted bodily for substantially encircling the water line portion of the ship.

In the drawing forming a part of this application, and in which like reference characters denote corresponding parts throughout the several views,

35 Figure 1 is a side elevation of a ship provided with the present device,

Fig. 2 is a vertical transverse sectional view through a portion of the device showing the elevating means employed,

Fig. 3 is a top plan view of the bow portion of a ship provided with the device, parts being broken away and

40 Fig. 4 is a top plan view of the operating means for the elevating devices which are employed.

The present invention is herein illustrated in connection with a ship 10 having a hull 11, a deck 12, cabin 13 and wireless mechanism 14.

45 Curved mattresses or shields 15 of material suitable as armor, as metal, are arranged with their forward ends pivoted together as at 16 and being positioned upon opposite 50 sides of the hull for substantially inclosing the same with the connection 16 forwardly

of the bow 17 thereof, connecting clamps 18 being secured between the rear ends of the shields 15 surrounding the stern portion 19 of the hull.

60 Upright racks 20 are secured to the shields 15 freely passing vertically through brackets 21 arranged adjacent the deck 12 of the hull 11 the said racks being slightly resilient while spacing springs 22 are carried by the 65 inner sides of the shields 15 for slidably engaging the outer surface of the hull 11. Pinions 23 are mounted upon shafts 24 journaled through brackets 25 upon the deck 12 adjacent the brackets 21, the said pinions 23 70 being in mesh with the teeth 26 of the racks 20.

The shafts 24 may be operated in any desired manner such as by means of sprocket chains 27 passing over sprocket wheels 28 75 adapted for operative connection with and released from the shafts 30 by means of clutches 29 while the chains 27 also pass over sprocket wheels 31 carried by the shaft 24, it being understood that the shafts 30 80 are power shafts operable either by hand or by motor not shown.

The shields 15 which, as heretofore stated are of metal, are formed of laminations having their outer layers and intermediate layers 32 formed of strips longitudinally arranged while the intervening layers 33 extend vertically of the shields. This formation of shields is adapted for rendering the same impenetrable by torpedoes or projectiles striking the shields from either side of the ship 10 while the shields 15 are readily adjusted for covering the hull 11 adjacent the water line and whereby the ship is protected from attack from torpedoes which are 95 launched from submarines.

A complete operation of the device having been already described, it will be understood that the preferred embodiment is herein set forth, but that minor changes may be made 100 therein without departing from the spirit and scope of the invention as claimed.

What we claim as new is:—

1. A protector for ships comprising elongated shields formed of laminated longitudinal and transverse strips, pivotal connections between the forward ends of the shields, clamp connections between the rear ends of the shields, spacing springs carried by the inner faces of the shields and elevating means for the shields.

2. A device of the class described, com-

prising in combination with a hull having a deck, curved elongated laminated shields adapted for substantially inclosing the hull at the water line thereof arranged at opposite sides of the hull, pivotal connections between the forward ends of the shields, clamps between the rear ends of the shields, springs carried by the inner faces of the shields, slidably contacting the hull, projecting brackets carried adjacent the top of the hull, upright resilient tilted racks carried by said shields, slidably arranged through the said brackets, shafts journaled upon the deck of said hull, pinions carried by said shafts in constant mesh with said racks, and operating means for said shafts arranged upon the deck of the ship.

3. A protector for ships, including shields adapted to conform to the general outline of the hull, at the waterline, with their forward ends pivoted together forwardly of the

bow and their rear ends extending to, and connected together in rear of the stern, spacing means between the shields and the hull, and means for suspending the shields 25 in position from the deck.

4. A protector for ships, including shields adapted to conform to the general outline of the hull, at the waterline, with their forward ends pivoted together forwardly of 30 the bow and their rear ends extending to, and connected together in rear of the stern, resilient spacing means intermediate of the shields and the hull, and means for suspending the shields in position from the deck. 35

In testimony whereof we affix our signatures in presence of a witness.

CARL SMYRSKI.
JAN LORENC.
